UNITED STATES PATENT OFFICE.

RENSSELAER H. TOLL, OF BERKELEY, CALIFORNIA.

COMBINED BOOK PULL AND MARKER.

1,266,885.

Specification of Letters Patent.

Patented May 21, 1918.

Application filed May 29, 1917. Serial No. 171,731.

To all whom it may concern:

Be it known that I, RENNSSELAER H. TOLL, a citizen of the United States, and a resident of Berkeley, in the county of Alameda and 5 State of California, have invented certain new and useful Improvements in a Combined Book Pull and Marker, of which the following is a specification.

The present invention relates to articles of 10 stationery, and more particularly to a device adapted to be applied to books and the like, as a pull and marker.

An object of the present invention is to provide a light and simply constructed device 15 which may be applied to books as markers therefor, and which are of such construction as to overhang the top and back of the book and be readily accessible to the fingers when the books are arranged in rows upon 20 a shelf or the like, for the purpose of withdrawing the books.

The invention further aims at the provision of means for dislodging a book from a row of books on a shelf without grasping 25 and tearing the binding of the book, and without disturbing the next adjacent books. The device of the present invention is adapted to admit of the removal of books on closely vertically spaced-apart shelves, 30 and to admit of the maintaining of the backs of the books in transverse register throughout the length of the row of the same.

The above, and various other objects and advantages of this invention will be in part 35 described, and in part understood from the following detailed description of the present preferred embodiment, the same being illustrated in the accompanying drawing, wherein:

40 Figure 1 is a perspective view of several of the devices of this invention applied to books, the view illustrating the operation of one of the devices for withdrawing a book from a row of the same.

45 Fig. 2 is a side elevation of the combined book pull and marker.

Fig. 3 is an outer end elevation of the same.

Fig. 4 is a transverse section, enlarged, 50 taken substantially on the line 4-4 of Fig. 2, and looking toward the upper end thereof.

Referring to this drawing, the device comprises a single length or strip of flat metal which is relatively narrow and of sufficient 55 thickness to provide a relatively rigid structure. One end of the metallic strip is bent

upon a transverse line at substantially right-angles to the body portion of the strip, to provide a depending lug 10 terminating at its lower end in an outturned lip 11. The 60 body portion of the strip comprises a connecting arm 12 adapted to extend over the upper edge of the back A of the book, and to be drawn outwardly thereover, when the finger is engaged beneath the lug 10, as 65 shown in Fig. 1.

The inner end of the arm 12 is provided with a depending blade 13, which comprises a flat portion of the strip which is twisted to lie in a plane substantially at right angles 70 to the plane of the arm 12, and which is bent downwardly upon a transverse line into substantially parallelism with the lug 10. The blade 13 is relatively long and is adapted to extend downwardly between the leaves of 75 the book A to a considerable extent for anchoring the device in the book, and to also serve as a marker for designating any desired place in the book.

As shown in Fig. 4, the opposite marginal 80 edges of the blade 13 may be beveled to provide cutting edges for the purpose of serving as a paper cutter for the separation of leaves in a book which have not been separated and for such other convenient uses for 85 which paper cutters are adapted.

If desired, the outer face of the lug 10 may be provided with suitable indicia 14 for indexing or labeling the book, or for lending ornamentation to the device. 90

Normally, the device is adapted to be inserted between the pages of a book as shown in Fig. 1, with the lug 10 lying close against the back of the book A. When it is desired to withdraw the book, the finger is inserted 95 between the lip 11 and the book, and the lug 10 is drawn outwardly sufficiently to engage the finger back of the lug. The lug is now drawn forwardly, and the arm 12 slides over the top of the back of the book, and the 100 blade 13 catches in the book between the leaves. When the device is thus pulled forwardly, the book may be tilted as shown in Fig. 1 sufficiently to grasp the side covers of the book for removing the same from the 105 row without disturbing the next adjacent books. By the provision of this device, it is unnecessary to engage the fingers with the top of the book, as is the ordinary custom, and where the shelves are arranged in closely 110 vertically spaced-apart relation, it is unnecessary to dislodge the adjacent books for the

purpose of grasping the book desired. The devices may also be employed as detachable index labels or tags for separately designating the books according to various indexes or the like which may be employed.

It is of course understood that various changes and modifications may be made in the details of construction and design of the above specifically described device, without departing from the spirit of this invention, and being restricted only by the scope of the following claims.

I claim:

1. A combined book pull and marker comprising a single length of strip metal bent near one end at substantially a right angle to the transverse plane of the strip to provide a finger receiving lug, and bent in a like

manner near its opposite end and twisted thereat into a plane at right angles to the transverse plane of said lug to provide a blade for insertion between the leaves of a book to anchor the device therein.

2. A combined book pull and marker comprising a flat metal strip adapted to lie along the upper edge of a book with one end projecting over the back thereof, the strip having on its other end a depending blade adapted to lie between the leaves of the book and limit the sliding of the strip over the back thereof, the strip also having a depending finger engaging lug on said first end adapted to be drawn outwardly from the back by the fingers for withdrawing the book from a shelf.

RENSSELAER H. TOLL.
